UNITED STATES PATENT OFFICE.

LEON P. LEWANDOWSKI, OF LOUP CITY, NEBRASKA.

POCKET FOR GARMENTS.

Application filed June 3, 1926. Serial No. 113,528.

This invention relates to pockets for garments and has for an object to provide an improved construction which may be applied to wearing apparel of any kind and caused to function in the same manner regardless of the garment on which it is applied.

Another object of the invention is to provide a pocket structure in which the parts are so arranged that coins in the pocket cannot readily move out of the pocket even when the same is inverted.

A still further object of the invention, more specifically, is to provide a pocket for coins and other articles which is pleasing in appearance and which may be made in different sizes and caused to function in the same manner regardless of size.

In the accompanying drawing—
20 Figure 1 shows a pocket embodying the invention, the same being shown for the purpose of illustration as applied to gloves.

Figure 2 is an enlarged fragmentary sectional view through Figure 1 on line 2—2.
25 Figure 3 is an elevation of a pocket showing a different form of the invention from that illustrated in Figure 1, the same being illustrated on a glove.

In manufacturing the pocket embodying the invention, the same may be applied to garments of any kind and may be arranged at any desired point on any garment. For the purpose of illustration, the same has been shown as applied to gloves in the accompanying drawing. Referring to the drawing by numerals, 1 indicates a glove of any desired kind which is provided with a pocket 2 mounted on the back. It is evident that the pocket could be mounted at some other point without departing from the spirit of the invention.

In forming the pocket 2 the same is provided with a body 3 which is round except at the top where it is preferably formed with a straight section 4. The body 3 is held in place by a suitable line of stitching 5 and at a point spaced from the top and bottom is provided with an opening 6. This opening is normally covered by a flap 7 which is preferably arc-shaped and preferably held in place by a line of stitching 8

extending through the body 3 and the flap 7. This flap covers the opening and prevents to a certain extent any contents from passing through opening 6 as well as presents a structure having a pleasing appearance. By reason of the spacing of the opening 6 from the top and bottom and also from the sides, said opening will readily permit articles to be placed in the pocket 60 but will prevent articles from being accidentally moved therefrom. In case a coin was placed in the pocket and the pocket was inverted, the coin would pass by the opening 6 and stop when engaging the line of 65 stitching at the edge 4. When the pocket was again moved to a correct upright position the coin would merely slide back to its former position at the bottom of the pocket. Though a coin or other article cannot accidentally pass through the opening 6, a 70 person may readily move the article through the opening.

In Figure 3 a slightly modified construction of pocket is shown wherein body 3' is 75 formed many sided, namely, octagon shape and is provided with an arc-shaped flap 7' and this flap can be of some other shape if desired.

What I claim is:

1. A pocket for a garment comprising a body superimposed on the garment and having an entrance opening spaced from the top, bottom and sides, and a flexible covering flap connected to the body immediately above the opening, said flap being spaced from the edges of the body and normally overlapping the opening.

2. The combination with a garment, of a pocket therefor formed with a body consisting of a single sheet of material having an opening spaced from the top, bottom and sides, a line of stitching around the edge of the sheet of material extending through said sheet and through part of the garment for 95 connecting the sheet to the garment, and a flap normally covering said opening, said flap being connected to the sheet near one edge of the opening and spaced from the edges of said sheet.

LEON P. LEWANDOWSKI.
